(57) **CLAIM**

The ornamental design for a case with electronic device with display or portion thereof with graphical user interface as shown and described.

DESCRIPTION

FIG. 1 is a front view of a case with electronic device with display or portion thereof with graphical user interface showing the claimed design;

(Continued)

FIG. 2 is a rear view thereof;
 FIG. 3 is a left side view thereof;
 FIG. 4 is a right side view thereof;
 FIG. 5 is a top view thereof; and,
 FIG. 6 is a bottom view thereof.

The broken lines in the figures show portions of the case with electronic device with display or portion thereof with graphical user interface that form no part of the claimed design.

1 Claim, 3 Drawing Sheets
